ASSIGNORS TO THE NO-MAR MANUFACTURING COMPANY, OF CLEVELAND, OHIO,
A CORPORATION.

DRY MOP.

1,036,542.

Specification of Letters Patent. Patented Aug. 27, 1912.

Application filed February 6, 1912. Serial No. 675,900.

To all whom it may concern:

Be it known that we, GORHAM F. BASSET, MARSHALL F. CLAY, and JOHN J. PHARE, citizens of the United States, residing at 5 Cleveland, in the county of Cuyahoga and State of Ohio, have invented certain new and useful Improvements in Dry Mops, of which the following is a specification.

Our invention relates to an improvement 10 in dry mops, or mops intended to be used dry for cleaning hardwood floors and the like and where wiping rather than washing or scrubbing is the preferred practice. These dry mops however, are generally saturated slightly with oil which helps to absorb the dust, and gives an oil finish.

In the accompanying drawings, Figure 1 is an elevation of the mop partially in section, and Fig. 2 is an elevation in section on 20 line 2—2, Fig. 1. Fig. 3 is a plan view of the mop on line 3—3, Fig. 1, and Fig. 4 is an end elevation of the staple plate on the mop through which it is engaged with the frame and handle. Figs. 5 and 6 are elevations at 25 right angles to each other of a modification of the invention wherein the engagement of the spring wires in the mop are directly opposite to what is shown in Figs. 1 and 2. Fig. 7 is a side elevation of the mop alone 30 with a fastening plate having side flanges with holes for a holder adapted to clamp from the sides instead of the ends, and Fig. 8 is a cross section showing side holder arms engaged in said holes. Fig. 9 is a plan view 35 of the mop as shown in Fig. 7.

The present invention is an improvement on the construction shown in an application filed by J. J. Phare and M. F. Clay, Ser. No. 647,468, and is intended to provide means 40 for making working connection between the handle and the mop which is more convenient than that shown in the said application and especially avoids engaging the spring arms in holes through the body of the mop. 45 To these ends we show several different ways of connecting said parts, and in Figs. 1 to 4 inclusive we employ a handle *h*, spring arms *a* having threaded connection on the end of the handle as before, and also a cross 50 bar *c* having openings through which arms *a* are slidably projected. Bar *c* is rotatably fixed by screw to the end of the handle as before. The ends 7 of the said arms are bent at right angles outward also as before, but 55 in this case the bar *c* is of channel iron pat-

tern with the channel down and the mop *m* has a plate *d* of sheet metal permanently fixed on the top or back thereof by means of prongs 5, which may be of any number and located at the ends or at intermediate points 60 of the plate. These prongs pass through the body of the mop and are tightly clenched on the under side. In addition to this the said plate has ears 6 struck inward at each end and which have eyes adapted to receive the 65 ends 7 of the spring arms as said arms are inserted from the top through the elongated holes in said plate made in part by striking the said ears therefrom. The spring of said arms holds the said ends 7 in engaging position with ears 6, but locking is effected after this engagement has been made when the handle *h* is rotated and the cross bar *c* and plate *d* are drawn together in tightening relation. 75

In Figs. 5 and 6 the ears 6' on the staple plate *d'* are struck down from the immediate ends of said plate and arms *a* engage from without inward in the said ears 6 instead of from within outward as in Figs. 1 and 2. 80

In the further modification, Figs. 7 and 8, the staple plate *d''* has side flanges 8 with eyes 9 in the ends of the flanges and adapted to receive a spring arm or other fastening device in each of said eyes. As to this it should 85 be understood that one form of means for engaging with the said eyes is shown in Fig. 8, but that any other suitable construction may be employed.

In all the views the ears 6 and the flanges 90 8 make room for connection by the arms *a* by pressing the stock or strands of the mop inward out of the way and thus permitting the said right angled ends 7 to be engaged laterally through said ears or flanges over 95 the head of the mop. This construction also brings the top surfaces of mop *m* and plate *d* in substantially the same plane or flush with one another.

The mop *m* is made of parallel strands of 100 fabric secured together by a flexible band *b* of heavy woven fabric about its middle, and the staple plate with its prongs is fastened through this portion which is also referred to as the head of the mop. The plate itself 105 fixed thereon is a practically rigid part, but shorter than the width of the mop and narrower than band *b* so as to leave a considerable surplus of the stock at each side and thus prevent possible contact of the ends 110

or edges of said plate with furniture or other articles having delicate and easily marred surfaces when the mop is being used.

If two staple plates or two small plates were stapled in position and having each a lateral eye for engagement by arms *a* the effect would be the same as with a single plate having two or more eyes for the same purpose. But one elongated plate is better than two, as the intermediate portion 4 thereof stiffens the mop centrally between ears 6 and prevents the mop from gathering together or stretching apart between these points of attachment with the handle.

15 What we claim is:

1. A mop provided with a device having prongs, the latter being engaged through the mop and having eyes at the sides thereof, and a handle provided with arms engaged laterally through said eyes.

2. A mop for dry cleaning floors and the like consisting of strands of flexible material and a band of flexible material about the middle thereof, in combination with a plate

having prongs engaged in the said mop 25 through said band and having eyes at its bottom and ends, in combination with a handle and spring arms on said handle having their ends removably engaged in said eyes. 30

3. A mop for dry cleaning floors and the like consisting of strands of flexible material having a flexible band about the middle thereof and a plate secured on said mop having holes therein, in combination with a 35 handle, spring arms adjustable on said handle and engaged in said holes and a cross-bar fixed on said handle having holes in which said arms are slidably engaged, thus making a detachable mop. 40

In testimony whereof we affix our signatures in presence of two witnesses.

GORHAM F. BASSET.

MARSHALL F. CLAY.

JOHN J. PHARE.
